UNITED STATES PATENT OFFICE.

GEORGE LANGFORD, OF JOLIET, ILLINOIS, ASSIGNOR TO AMERICAN MCKENNA PROCESS COMPANY, OF MILWAUKEE, WISCONSIN, A CORPORATION OF WISCONSIN.

STEEL RAIL FOR RAILROADS OR THE LIKE.

1,212,964.

Specification of Letters Patent. Patented Jan. 16, 1917.

Application filed May 19, 1915. Serial No. 29,041.

To all whom it may concern:

Be it known that I, GEORGE LANGFORD, a citizen of the United States, residing at Joliet, in the county of Will and State of Illinois, have invented a certain new and useful Improvement in Steel Rails for Railroads or the like, of which the following is a full, clear, concise, and exact description, reference being had to the accompanying drawings, forming a part of this specification.

This invention relates to steel rails for railroads, or the like.

The chief object of the present invention is to provide a rail of maximum efficiency.

It is a further object of the invention to provide a rail of such design as to enable the same to be employed for special or general track purposes with a maximum degree of utility.

A further object is to provide a track construction employing standard rails and special rails of an improved design which are so formed as to improve the operating characteristics of rolling stock thereupon.

The rail which is the subject-matter of the present application may appear in a variety of forms, each containing the underlying idea of so placing the metal as to secure the greatest utility thereof, and to meet, as fully as possible, all the apparently conflicting conditions which are to be met in designing a rail that is applicable to a variety of uses and conditions.

Heretofore in the art it has been deemed essential to have the rail constructed on a symmetrical pattern. I find it highly advantageous to separate the various functions which the rail is required to perform, and to design one part of the rail to take care of one function and another part of the rail to take care of another function. In this manner I am enabled to secure a design of rail in which the metal will be disposed to the best advantage.

Under conditions of operation a railroad rail is subjected to wear which may be classified as follows:

First, the wear due to actual grinding down of the tread of the rail, which affects the depth of metal in the head;

Second, the grinding away at the side of the head due to grinding action of the wheel flanges. This effect causes a decrease in width of the tread;

Third, the wear due to transverse motion, or transverse forces between the face of the wheel and the tread of the rail. This causes a sidewise flow of the metal at the upper outer corner of the head; and, fourth, the wear on the bottom sides of the head due to friction at the joints. This changes the contour of the fishing, where the joints or angle-bars connect the ends of the rails.

The first three types of wear may be compensated for by properly disposing the metal of the upper part of the head in accordance with my invention; and the last type of wear may be corrected by a proper disposition of the metal of the lower part of the head, in accordance with my invention.

I shall now describe, in connection with the accompanying drawings, which form a part of the present specification, the manner in which my invention may be employed in practice.

Figure 1 is a chart illustrating approximately the various degrees and amounts of wear that a rail may be subjected to and the approximate form that the rail will assume under varying conditions. (A) illustrates a degree of wear such as might occur on tangent track. The rail is taken out because of destruction of the fishing. (B) illustrates a worse condition. (C) illustrates a further degree of wear. (D) illustrates a badly worn rail such as might occur on the outer rail on a curve. (E) illustrates a worse condition such as may occur under the same condition. (F) illustrates a type of worn rail such as occurs on the inner rail of curves.

In Fig. 2 I have illustrated, in outline, the cross-section of a standard 100-lb. rail, together with the angle-bars for forming the joint.

In Fig. 3 I have shown, in outline, a section of a rail constructed according to my invention.

In Fig. 4 I have illustrated a modification carrying still further the principles of my invention.

In Fig. 5 I have illustrated a different embodiment; and, in Fig. 6 I have shown a diagrammatic illustration of a section of track employing rails constructed in accordance with my invention.

Fig. 2 shows, in outline, a standard 100-lb. rail with the angle-plates 1 and 2 forming the joint. These plates are wedged between

the head 3 and the base or flange 4, and form struts or girders between the ends of rails to form continuous track.

Assuming that the left-hand face 5 is the gage side, it will be seen that as the flanges of the wheels scrape past this surface the metal will be ground away and eventually the metal would be ground away to such a point that if the depth of head 10 were not greater than the width of the flange of the wheel, the flange would eventually strike the angle-bar at 20. At the same time the wear upon the tread 6 caused by rolling and pounding of the wheels, by slipping of the wheels due to braking, and to the driving wheels of engines, will grind away the metal of the head, thus lessening the depth of head. This also tends to bring the flange of the wheel closer to the angle-bar 2, so that as these two degrees of wear increase the flange will eventually strike the angle-bar 2 at 20 and the rail, according to good practice, must then be taken out of the track. At the same time the metal flows 25 outward in the upper head corner 9 on the right-hand side, due to combined vertical and lateral forces and motion of the wheels.

If it were desired to increase the strength or wearing qualities of the section, the head might be made deeper and thicker, but, considered from a metallurgical standpoint, this would not be good practice, since the rate of cooling of the head would be very 35 much below that of the web and the flange and internal stresses would be set up which would be injurious to the quality of the rail. Furthermore, the rail would warp excessively on cooling and would require excessive 40 labor to straighten it. Hence, the prior art has taught an increase in all the dimensions of the section where it is desired to secure greater strength. A perfectly symmetrical rail employs a percentage of metal 45 on the outer side of the head which adds very little to the strength and possibly nothing to the wearing qualities.

According to my invention, I construct the rail with the gage side particularly 50 adapted for wear, and construct the outside of the rail with the idea of attaining girder strength and maintaining a full bearing between the bottom of the head and the top of the angle-bars.

55 In Fig. 3 I have shown, in outline, one form in which the rail may be constructed. This section is shown as having the flange 4 and the web 11 constructed substantially in accordance with the standard dimensions 60 of a given weight of rail; in fact the entire left side of this rail is constructed in outline following the contour of a standard section of rail. The right side follows the contour of a standard new rail so far as the 65 fishing, the web and the flange are con-

cerned; but the outer face of the head 10 slopes upward and inward, so that this side of the head is considerably lighter than the other half. This type of construction allows of a very decided advantage in providing a section such that added metal can be placed at the point where it is needed without undue increase in weight of the rail. The width of angle-bar bearings is as great as that obtained in standard rails and may, 70 if desired, be made greater upon the outer or right-hand side, as shown in Fig. 3. By properly forming the angle of the side 10 it is possible, first, to control the width of tread; second, to control the amount of metal in the head and to dispose the same so that the amount of metal for wear or for joint bearings may be properly distributed; third, control of the metallurgical difficulties incident to cooling, and the like, by securing greater surface. The tapered side 10 also provides greater strength against sidewise flow of the metal at the corner 9. As the tread 6 and the side 5 of the rail wear down and in, there is an automatic 85 compensation due to the tapered side 10, so that the tread remains substantially constant. This form of rail is designed to be interchangeable with standard rails as employed by the various railroads, or interchangeable with the particular standard employed by any particular railroad. I have found that it is possible to produce this shape and style of rail from badly worn rails which would otherwise be classed as 90 scrap. In a co-pending application, Case 2, I have disclosed a method whereby a badly worn rail may be shaped into this style of rail at a very slight cost, so that the worn rail may be replaced in the track and used further so as to prolong, to a great extent, 95 the useful life of the rail.

As outlined in the co-pending application above referred to, I find that it is possible to take rails which are badly worn, as shown at D in Fig 1, and, by the process particularly set out and claimed in that application, I am enabled to bring the rails to the shape shown in Fig. 3. This process consists, briefly, in heating the worn rails to a point below the temperature at which the physical condition of the steel would be injuriously affected; then running the same through properly shaped rolls to bring the rails to the general outline or cross-section shown in Fig. 2. The ends of the renewed rails are then sawed off, still leaving the rail at approximately the original length.

The qualities which characterize the outline shown in Fig. 3 are that the rail so renewed or treated shall have the same general standard dimensions, or substantially the same, as the original rail with the exception that the width of tread has been decreased 125 by changing the taper on one side of the 130

head, the fishing has been restored, the rail has been trued up and straightened and the metal has been redistributed.

Rails of the section such as shown in Fig. 3 may be employed on tangent track and may be employed to particular advantage on curved track where the slope of the side 10 has been made so great as to materially reduce the tread 6 of the rails.

10 In Fig. 6 I have shown the rails 17, 18 and 19 as being of the structure shown in Fig. 3 and having a considerably narrower tread than the standard rails to which these rails are connected to form a track. I wish 15 it to be understood, however, that I do not intend to limit the use of the rail embodying my invention to any particular position in the track, but intend that the same may be used wherever found advantageous; the 20 teaching of my invention being, broadly, a correct disposition of the metal in the head of the rail to secure maximum wearing surface and maximum strength with a minimum of material.

25 Fig. 4 shows a structure in which the left side of the rail corresponds to the general contour of a standard rail. This side of the rail is employed to secure the best possible 30 wearing qualities. The right side of the section has been designed to obtain maximum strength and to this end the width or depth of the fishing has been increased so as to obtain greater girder strength at the joint. If desired, the fishing on the gage 35 side may be decreased in depth so as to obtain a greater depth of head at the side 5. The bearing surfaces 7 and 8 may either one be broadened, if desired, to obtain an increased wearing surface of the angle-bar 40 on either side. The web and flange are preferably made symmetrical.

Fig. 5 is a further employment of the principles found in the structures of Figs. 3 and 4 and provides a rail in which the left side is designed to obtain increased 45 wearing qualities, while the right-hand side has been designed to obtain greater strength at the joint.

50 The two sides of the rail have purposely been made unsymmetrical, with the idea that the greater depth of head on the side 5 can be used to decided advantage on curved track. Each side of the head may be made wider so as to obtain a greater bearing area 55 between the bottom of the head and the angle-bars 1 and 2. The increased depth of fishing also secures greater girder strength of the angle-bar and greater 60 strength of the rail for the same weight of metal, so that this side of the rail makes up in strength for the loss on the service side of the rail, without unduly increasing the height or weight of the rail itself. The 65 rail is also capable of being reversed and em-

ployed with the narrower depth of head on the flange side, if so desired.

Fig. 1 shows in chart form a comprehensive scheme for renewing rails. The rails as they are taken up from the track 70 are sorted out according to the degree of wear. Fig. 1 illustrates a scheme of grading which I may employ. The grade shown at A may be renewed into a symmetrical rail, as shown and described in my co-pending 75 application (Case 1). The grades shown at B and C may be similarly renewed into symmetrical standard rails, as there described. Or the grade shown at C may be renewed into the narrow-tread rail for 80 curves as described in my co-pending application Case 4.

The grade shown at D may be renewed 85 into the form shown in application Case 4, to be used for curves; or, where the metal is sufficient to give a fairly wide tread, the rail may be used in tangent track, as set out in the present application.

The grade shown at E (Fig. 1) may be renewed into the maximum utility type of 90 unsymmetrical rail as set out in the present application, usable either on curved or tangent track.

The grade shown at F (Fig. 1) may be renewed into the maximum utility rail de- 95 scribed in the present application.

I do not intend to be limited to grading the rails in the precise manner above set out, the above being only one scheme for doing the same.

100 By properly proportioning the various dimensions the various qualities which may be desired can be controlled so as to obtain a rail to meet any particular condition or requirement.

105 What I claim as new and desire to secure by Letters Patent of the United States is:

1. A railroad rail comprising a service or wearing side and a strength side, the service side comprising head, web and flange 110 portions of substantially standard dimensions, the strength side comprising a flange portion similar in all substantial respects to the flange portion of the service side, a web portion of greater height than the web 115 portion of the other side, and a head portion having full bearing surfaces for the angle-bars, but comprising less metal than the head portion of the other side said rail comprising less metal per unit of length 120 than a standard rail.

2. A railroad rail adapted for use in connection with standard rails, comprising a service side, and a strength side, said service side comprising head, flange, and web 125 portions of substantially standard dimensions, so as to match up with standard rails, said strength side comprising a head portion of substantially standard width, a flange portion of substantially standard di- 130

mensions and a web portion of greater depth than the web of a standard rail.

3. A railroad rail adapted for use in connection with standard rails, comprising a 5 service side and a strength side, said service side comprising head, flange, and web portion of substantially standard dimensions, so as to match up with a standard rail, said strength side comprising a head 10 portion of substantially standard width to give full bearing surface for the angle-bar, and a tapered side to reduce the tread of the rail and to produce a lighter rail head, a flange portion of substantially standard 15 dimension, and a web portion of greater depth than the web of a standard rail, whereby said rail has its gage side substantially in conformity with standard contour and dimensions, but the entire rail is lighter 20 per unit of length than a standard rail.

4. In a railroad track, a rail substantially standard in all its dimensions except as to a decrease of tread surface, said dimensions including flange, web, and fishing, the inner 25 side of the head of said rail conforming to the outline of a new standard rail, and the

outer side of the head having substantially the same width at the base thereof and the same contour of the parts joining the web, but having its side face tapered in toward 30 the top to conform to the general contour of wear of a worn rail, the depth of head being substantially standard, a standard rail placed end to end with said rail, and standard angle-bars joining the same to form a 35 continuous track.

5. A railroad rail substantially standard in all its dimensions except as to the head and the fishing of one side, said head being unsymmetrical, the inner side of said head 40 conforming substantially to the outline of a new standard rail, and the outer side of said head having its side sloped inward but being of substantially standard width and contour at the base thereof, the fishing, the 45 web and the base of said rail being substantially standard in all respects so as to be capable of use with standard fittings such as may be employed with new standard rails.

In witness whereof, I hereunto subscribe 50 my name this 17th day of May, A. D. 1915.

GEORGE LANGFORD.
